Primary Examiner — Susan Moon Lee**CLAIM**

The ornamental design for pet bowl, described in appearance and pattern, as shown and described.

DESCRIPTION

FIG. 1 is a top perspective view of a pet bowl showing my new design;

FIG. 2 is a bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom view thereof.

Broken lines and portions contained within broken line are not claimed.
